UNITED STATES PATENT OFFICE.

HUGO LENTZ, OF BEELIN-HALENSEE, GERMANY.

FLUID CHANGE AND REVERSING GEAR.

1,128,010.

Specification of Letters Patent.

Patented Feb. 9, 1915.

Application filed October 21, 1914. Serial No. 867,891.

To all whom it may concern:

Be it known that I, HUGO LENTZ, a citizen of the German Empire, and resident of Berlin-Halensee, Germany, have invented 5 certain new and useful Improvements in Fluid Change and Reversing Gears, of which the following is a specification.

My invention relates to improvements in fluid change and reversing gears, such as are designed for controlling the transmission of power from a prime mover through pumps and motors driven by the pressure medium from said pumps to a secondary or driven mover. Such gears are used for example on board of ships for transmitting power from the engine to the propeller shaft.

The object of the improvements is to provide a gear of this class by means of which 20 a set of fluid operated motors is connected at least with two sets of pumps in such a way that the pressures of the fluid transmitted from the sets of pumps to the set of motors cause a balancing of the pressures 25 on the set of motors.

Another object of the improvements is to provide by-passages and compensating passages by means of which the direction of rotation of the driven shaft can easily be 30 reversed, and which in case of non-uniform power of the sets of pumps compensate the power within the gear.

For the purpose of explaining the invention an example embodying the same has 35 been shown in the accompanying drawing, which is a section of the gear in which the controlling elements are shown in the positions for forward movement of the driven mover.

40 In the example shown in the drawing two sets of pressure pumps *b* and *c* and a set of motors *d* of the construction common in rotary machines are located within a casing *a*. The two sets of pressure pumps *b* and *c* 45 are disposed symmetrically and at opposite sides of the set of motors *d*, and the chambers *e'*, *f'*, and *g'*, *h'* of said pumps are connected with the motors *d* through passages *e*, *f* and *g*, *h* respectively which are 50 located tangentially of the sets of pumps and motors. The said passages are equipped with controlling members or valves *i*, *k* and *l*, *m* respectively. In the symmetrical arrangement shown the two passages *e*, *h* 55 which have the same function are parallel to each other, and the same thing is true of

the other pair of passages *f*, *g*, and the two passages of a pair lead to the motor *d* at diametrically opposite points.

The chambers *e'*, *h'* are pressure chambers, and the chambers *f'*, *g'* are suction chambers when the pumps rotate in the direction indicated in the drawing, and the passages *e*, *h* are pressure passages, while the passages *f*, *g* are suction passages when 60 the valves *i*, *k*, *l*, *m*, are in the position shown in full lines. In the casing *a* there are arranged laterally passages *nn*, *oo*, *s*, and *t*. Of these, the passages *nn* and *oo* lead from the pressure passages *e* and *h* 65 respectively to the controlling members *k* and *l* respectively, which according to their position will establish or interrupt the connection of said passages *nn* and *oo* with the suction chambers *f'* and *g'* respectively. 70 The compensating passage *s* connects the passages *e* and *o* with the passages *h* and *o*, while the compensating passage *t* connects the passage *f* with the passage *g*.

The operation of the apparatus is as follows: When the apparatus is moving in forward direction the controlling members *i* and *k* or *l* and *m* are in the positions shown in the drawing. The shafts *p* and *q* of the two sets of pressure pumps *b* and *c* are 80 driven in the same direction each by a prime mover. The pressure fluid (ordinarily a non-elastic fluid) is forced from one of the sets of pumps, *b*, to one side of the set of motors, *d*, and from the other set of pumps, 85 *c*, to the opposite side of the set of motors *d*, so that the driven shaft is not subject to transverse pressure. Furthermore the current of the fluid moves in the form of a single elliptical band within a plane perpendicular to the shafts without being deflected from the said plane, so that the current of the fluid is not subjected to any 90 material resistance.

When I speak of the fluid as moving in 100 the form of a single elliptical band, I mean that the path of the fluid is a closed curve symmetrical to two axes which are perpendicular to each other; of course, the path shown in the drawing is not a true ellipse. 105 The major axis of said elliptical path extends through the axes of the pumps *b*, *c* and motor *d*. It will be seen that there are two entirely separate paths through which the liquid from the delivery port of one 110 pump passes to the suction port of the other pump. Thus for instance the path of the

liquid from the pump *c* to the pump *b* is entirely separate from the path of the liquid from the pump *b* to the pump *c*.

Now, if the shaft of one of the sets of pumps is driven with greater power than that of the other one, the power is balanced within the gearing itself through the compensating passages *s* and *t* in the following way: For example, if the set *b* of the pumps forces more liquid, one part of the said liquid acts in the regular way on the blades of the set *d* of the motors, while the other part of the liquid flows through the passage *s* to the other side of the set of motors and acts within the latter in the same direction on the blades. Of course, in this case the pump *b* will draw liquid partly through the passage *f* and partly through the passage *t*. The same is the case if the set *c* of pumps forces a greater amount of liquid.

If it is desired to reduce the speed, the pump pistons of one set of pressure pumps are thrown out of operation, as is known in the art. If it is desired to stop the driven shaft *r*, the two sets of pressure pumps are short-circuited by setting the controlling valves in the proper way that is to say, the valves *k*, *l*, are left in the position shown in full lines, but the valves *i*, *m* are placed in the position indicated by dotted lines. As a result, the liquid expelled by the pump *b* through pressure chamber *e'* will return to said pump through the passage *f* and suction chamber *f'*, and at the pump *c*, the liquid will pass from the pressure chamber *h'* directly to the passage *g* and to the suction chamber *g'*. To reverse the motor, the four valves *i*, *k*, *l*, *m*, are placed in the position indicated by dotted lines, which will cause the liquid to flow through the following path: From pump *b* through chamber *e'*, passage *f*, motor *d*, passages *h*, *o*, chamber *g'*, pump *c*, chamber *h'*, passage *g*, motor *d*, passages *e* and *n*, and back to pump *b* through chamber *f'*.

While in describing the invention reference has been made to an example in which two sets of pumps of equal power are provided, I wish it to be understood that my invention is not limited to this feature, and that more than two sets may be provided, and that the pumps may be so constructed as to develop different powers. Also in this case the driven shaft which rotates at lower

speed is perfectly balanced and the variations of the powers of the sets of pumps are balanced within the gearing itself.

My improved apparatus is particularly suitable for use on board of ships, because several non-reversible engines such as compound engines can be used.

I claim herein as my invention:

1. In an apparatus of the class described, the combination with a fluid motor, of pressure pumps, and suction and pressure passages for supplying the pressure medium from said pumps to the motor for driving the same, the discharge ends of the pressure passages being arranged symmetrically of the motor, whereby the fluid pressures acting on the motor are equalized relatively to the said motor, controlling members in said suction and pressure passages, and passages connecting the pressure and suction passages of the pumps.

2. In an apparatus of the class described, the combination with a fluid motor, of pressure pumps, and suction and pressure passages for supplying the pressure medium from said pumps to the motor for driving the same, the discharge ends of the pressure passages being arranged symmetrically of the motor, whereby the fluid pressures acting on the motor are equalized relatively to the said motor, controlling members in said suction and pressure passages, and compensating passages connecting the pressure and suction passages of the pumps between the controlling members and the motor, whereby differences of the power developed by the pumps are balanced.

3. In an apparatus of the class described, the combination with a rotary fluid motor, and rotary pumps located at opposite sides of said motor, the axes of said pumps and motor being parallel to each other and lying in the same plane, of passages connecting said motor and pumps and forming a continuous path of substantially the form of an ellipse whose major axis passes through the axes of the motor and of the pumps.

In testimony whereof, I have signed this specification in the presence of two subscribing witnesses.

HUGO LENTZ.
